UNITED STATES PATENT OFFICE.

DAVID L. REESE, OF LOS ANGELES, CALIFORNIA.

COMBINED OIL AND GAS BURNER.

1,195,500.

Specification of Letters Patent. Patented Aug. 22, 1916.

Application filed December 11, 1915. Serial No. 33,301.

To all whom it may concern:

Be it known that I, DAVID L. REESE, a citizen of the United States, residing at Los Angeles, in the county of Los Angeles and State of California, have invented certain new and useful Improvements in Combined Oil and Gas Burners; and I do hereby declare the following to be a full, clear, and exact description of the invention, such as will enable others skilled in the art to which it appertains to make and use the same.

My invention relates to new and useful improvements in combined oil and gas burner and is more particularly an improvement over my former Patent No. 965,407 dated July 26, 1910, and my object is to provide a burner having a depression therein to receive the liquid oil and arrange concentric ribs in the depression whereby the oil will be caused to flow slowly from the central to the outer portion of the hollow section of the burner.

A further object is to provide a gas chamber adjacent the peripheral edge of the burner having ports communicating with the upper surface of the burner.

A further object is to provide a deflector and so construct and position the same that when superheated the residue from the oil will be thoroughly consumed. And a further object is to provide means for supporting the deflector upon the burner.

Other objects and advantages will be hereinafter set forth, and more particularly pointed out in the accompanying specification.

In the accompanying drawings which are made a part of this application, Figure 1 is a central vertical sectional view through the burner with the deflector positioned thereon, and Fig. 2 is a top plan view of the burner with the deflector removed.

Referring to the drawings in which similar reference numerals designate corresponding parts throughout the several views, 1 indicates a burner which is preferably circular in general outline and provided with a cavity 2, at the central portion of which is formed a port 3 through which oil may be introduced into the cavity. Surrounding the port 3 and extending a distance above the floor of the burner is a circular rib 4 around which are concentrically arranged a plurality of ribs 5 which gradually diminish in height from the rib 4 outwardly thereby providing valleys 6 for the reception of the

oil as it leaves the port 3 and causing the oil to travel slowly toward the outer edge of the cavity 2.

Surrounding the cavity portion of the burner is an inclosed channel 7 into which gas is admitted through an opening 8, said gas escaping from the channel through a plurality of ports 9 in the upper face of the burner, and it will be readily seen that in view of the fact that the gas is separated from the oil, either product may be used singly for heating purposes or both used at the same time. In order to convey air to the burner and commingle the same with the gases so as to provide proper combustion and prevent undue carbonization, a deflector 10 is positioned above the burner and centrally over the cavity, said deflector having a central opening 11 through which air may be conveyed from any suitable source and discharged from the bottom of the deflector directly over the center of the burner. The under edge face 12 of the deflector is curved so that the products of combustion will readily pass around the deflector, said curved face causing the products of combustion to travel radially away from the burner and toward the walls of the stove or heating device in which the burner is located. The wall of the deflector is made of heavy material and very thick so that when the same becomes heated thoroughly, the heat will be retained and increased to such intensity as to burn the residue of the oil left in the valleys of the burner.

The deflector 10 is supported above the burner by providing arms 13 which are spaced apart and project outwardly over the upper edge of the burner and rest thereon, the outer ends of the arms having depending portions 14 which extend over the peripheral face of the burner and prevent the deflector from moving laterally thereon. By providing a combined gas and oil burner, it will be readily seen that should the supply of oil or gas fail, the other product can be used as a heating medium and further that should an intense heat be required both fuels may be used at the same time. It will likewise be understood that by providing the ribs whereby the oil is caused to flow over the base of the cavity slowly, the gases will be more readily extracted therefrom and by providing the form of deflector shown, after the same becomes thoroughly heated the residue of the oil will be thoroughly consumed.

Having thus fully described my invention what I claim as new and desire to secure by Letters Patent of the United States, is:—

1. A combination oil and gas burner having a central cavity therein, said burner having a port communicating with said cavity at its axial center, a rib surrounding the port and extending a distance above the floor of the cavity, a plurality of ribs concentric with the central rib and decreasing in height from the center rib to the edge of the cavity, said burner having a channel around its outer periphery for the reception of gas, the top wall of that portion of the burner over said channel having a plurality of ports therethrough through which the gas is discharged from the channel above the burner.
2. The combination with a burner, of a deflector having a central opening, the lower

outer surface of the deflector being convex 20 and uniformly curved from the central opening upwardly, supporting arms attached to the deflector, said arms having depending portions at their outer ends adapted to extend over and engage the peripheral face of 25 the burner, the body of said deflector being formed of thick heavy material whereby, when thoroughly heated any residue of oil in the burner will be consumed by the intense heat of the deflector.

In testimony whereof I have signed my name to this specification in the presence of 30 two subscribing witnesses.

DAVID L. REESE.
